UNITED STATES PATENT OFFICE.

ALBERT WESTLAKE, OF NEW YORK, N. Y.

BOTTLE.

1,116,523.

Specification of Letters Patent.

Patented Nov. 10, 1914.

Application filed November 18, 1913. Serial No. 301,793.

To all whom it may concern:

Be it known that I, ALBERT WESTLAKE, a citizen of the United States, and resident of the city, county, and State of New York, have invented certain new and useful Improvements in Bottles, of which the following is a specification.

My invention relates to that class of bottles to which a cap or seal of fibrous material is to be applied, and more particularly to bottles intended to contain milk, drinking-water, and other articles for daily distribution and use. It is desirable that the cap so applied should be practically air-tight so that the contents of the bottle may be protected against dust, dirt or other contamination; and that the cap should have a sufficiently firm hold upon the bottle-neck to resist the somewhat rough and hurried handling which such bottles receive during transportation and distribution. It is also desirable that such caps should be easily removed to get at the contents, and should be replaceable to the extent that after a portion 25 of the contents is removed the cap can be put on again and hold sufficiently for ordinary purposes of handling in domestic use.

As heretofore constructed, the bottles, milk bottles for instance, which have been capped by fibrous material have been provided only with the various types of bottle-neck rims or without such rim, but so far as I know, it has been found impossible to apply satisfactorily fibrous caps or closures 35 where the bottle has an exterior screw-thread upon its neck. While it has been found possible to mold the fibrous material over the protruding screw-thread with varying degrees of accuracy, it has also been 40 found that such capping was extremely uncertain, as most of the caps so applied failed to hold their grip, or to assume a shape conformed to such screw-thread.

It will be understood that the removal 45 and replacement of a fiber-cap upon a bottle having the ordinary bottle-neck rim depends upon the presence of a certain amount of springiness in the cap as formed so that it can be forcibly expanded by hand so as 50 to pass over the enlargement called the bottle-neck rim. The advantage of a screw-thread cap is that without springing or distorting the cap in any way, the cap may be turned on and off readily like any other 55 screw-threaded connection. Also that it

cannot be displaced by jars or handling in transportation or otherwise unless a twisting force is applied of sufficient duration to unscrew the cap, whereas with what may be called the plain topped bottle, a force sufficient to expand the cap enough to slip over the rim will remove the cap, whether said force is applied intentionally or not.

I have discovered that the practical difficulty in molding a fibrous cap upon a screw-threaded bottle neck lies in not being able to center the bottle with regard to the radial folding and tucking fingers by which the somewhat plastic cap is molded upon the bottle-neck. To overcome this difficulty I have devised a self-centering bottle which, by reason of its construction, compels every bottle to present its screw-thread in proper relation to the said fingers so that their action is precise and uniform.

One form of my improved bottle is shown in the accompanying drawing in which—

A is the body of the bottle.

B is the neck.

C is the projecting screw-thread, and D is the centering device which may be a depression, preferably triangular as shown, or a projecting stud if preferred. This centering device is an integral part of the bottle at its base and is designed to engage a suitable projection or recess as the case may be, upon the plate or table upon which the bottle is placed for the capping operation. This centering device D is, as shown in the drawing, located vertically under the opening a, of the screw-thread C as it is important that what may be called the beginning of the screw-thread fold of the fibrous material should always take place at the same position of the folding and tucking fingers. The rest of the operation follows naturally and accurately when the beginning is true.

In practice I have found that a pitch of a quarter of an inch is appropriate for a bottle-neck of one and one-half inches in external diameter, but the pitch may be made to vary with the size of the bottle-neck.

It will be found that my improved bottle will receive a fibrous cap put on by the usual and suitable capping heads or plungers as readily as if the bottle had an ordinary bottle neck rim, and that when so applied, the cap can be unscrewed and screwed on again at pleasure, practically as if it were a metal screw-cap.

The many advantages of this improved construction will, I think, be understood without further explanation.

with regard to the opening of said screw-thread formation that it insures the beginning of the capping operation in the proper position. 10

I claim:

3. A bottle provided with a screw-thread formation near the top of the bottle-neck for receiving a cap, and a centering device upon the body of the bottle and so located

ALBERT WESTLAKE.
